UNITED STATES PATENT OFFICE.

THOMAS MARKHAM, OF BELFAST, IRELAND.

FASTENING FOR DOORS, WINDOWS, AND THE LIKE.

1,136,430.

Specification of Letters Patent.

Patented Apr. 20, 1915.

Application filed August 29, 1913. Serial No. 787,278.

To all whom it may concern:

Be it known that I, THOMAS MARKHAM, a subject of the King of England, residing at Belfast, in Ireland, have invented certain 5 new and useful Improvements in Fastenings for Doors, Windows, and the like, of which the following is a specification.

This invention relates to improvements in fastenings for doors, windows and the like 10 of the type which permit the door to be locked in its closed position or held when opened, and the invention consists in a novel form of bolt comprising two pivoted parts, working in a casing having three cross slots, 15 into one of which the handle of the bolt engages when the door is locked, into another of which it engages when the door is unlocked, and into the third of which it engages when it is desired to hold the door 20 either in partly or fully opened position, the bolt being provided with a notch end which engages slotted keepers or equivalents for the two latter purposes.

The invention is shown in the accompanying drawings, in which—

Figure 1 is an elevation of the bolt; and Fig. 2 a plan view thereof; Fig. 3 is an elevation of the bolt, casing and keeper, and Fig. 4 a plan view of Fig. 3. Fig. 5 is a 30 plan showing a door fully open in full lines and held partly open in broken lines. Figs. 6 and 7 are views at right angles to one another of a keeper for use in holding the door fully open.

In said drawings *u* designates a door frame and *t* the door hung thereon. Mounted on the door is the casing *f* provided with three cross slots *g*, *h* and *j* and a longitudinal slot *k* and slidable within said casing is the 40 bolt formed of two parts *a* and *b* hinged together near the inner end at *c* and provided with a handle or equivalent *d*. The outer end of said bolt is provided with notches *e* of which two are shown, but one or any 45 other number of said notches may be provided.

Secured to the door frame *u* is a keeper *l* for reception of the bolt, this keeper having an angular projection *m* provided with a 50 hole *n* with which communicates a slot *p*, and to a wall or other fixed support there is attached a keeper *q* provided with a hole *s* communicating with a slot *r*. The slots *p* and *r* may be slightly tapered as shown.

The action of the fastening is as follows:—

When the bolt is completely withdrawn the shank of handle *d* lies in the slot *j* of the casing *f* and when the bolt is shot into the keeper *l* to lock the door the shank lies in the slot *h* (Figs. 3 and 4), these movements or 60 operations being as usual. When however it is desired to hold the door partly open, as shown in broken lines in Fig. 5, the bolt is shot fully forward in the casing, the shank traversing the longitudinal slot *k* and entering 65 the cross slot *g*. This brings the pivot *c* of the bolt beyond the end of the casing and the forward end of the portion *a* of the bolt is passed into hole *n* in projection *m*, one of the notches *e* therein then engaging the 70 slot *p*. Again, when it is desired to hold the door fully open, as shown in full lines in Fig. 5, the outer end of portion *a* of the bolt is passed into hole *s* in keeper *q* and a notch 75 *e* of the bolt will engage the slot *r*. The device is equally applicable for right or left hand use.

What I claim as my invention and desire to secure by Letters Patent of the United States is:—

1. A fastening for doors, windows and the like adapted for holding same in three positions, comprising a casing adapted to be secured to the door, a bolt within said casing formed of two members hinged together and capable of movement in said casing into two positions with its members in alinement and into a third position with one of its members angularly disposed, and keepers adapted to be secured to the door frame and a 80 fixed object with which said last mentioned member engages for the purpose of holding the door partly and fully opened respectively.

2. A fastening for doors, windows and the like, comprising a casing adapted to be secured to the door, a bolt within said casing formed of two parts hinged together and its outer end provided with notches, an operating member at the inner end of said bolt, 85 said casing having three cross slots and a longitudinal slot connecting same for reception of said operating member, a keeper adapted to be secured to the door or window frame and having a slotted aperture adapted to be engaged by the notched end of the bolt to hold the door or window in partly 90 opened position and a second keeper adapted to be secured to a fixed object and having a slotted aperture adapted to be engaged by 95 100 105 110 115

the notched end of the bolt to hold the door or window in fully opened position substantially as described.

3. A locking device for doors, windows and the like including a casing adapted to be secured to the door, said casing being formed with a longitudinal slot and transverse slots which intersect the longitudinal slot and which are disposed in spaced relation throughout the length of the casing, a bolt consisting of hingedly connected sections receivable as an entirety within the casing, the sections being maintained in axial alinement through contact with the casing, means for

locking the bolt against movement with respect to the casing whereby both sections are housed within the casing, means for locking one section of the bolt with respect to the casing whereby the other section may move on its hinge connection and means adapted to be carried by the door frame and engageable by the movable section of the bolt.

In witness whereof I have signed this specification in the presence of two witnesses.

THOMAS MARKHAM.
